(57) **CLAIM**

The ornamental design for a rake apparatus as shown and described.

DESCRIPTION

FIG. 1 is a perspective view of a rake apparatus showing my new design;

FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof;

FIG. 8 is a perspective view of the rake portion of the invention;

FIG. 9 is a front, perspective view of the vacuum portion of the invention;

FIG. 10 is a back, perspective view of the vacuum portion of the invention; and,

FIG. 11 is a back, perspective view of the rake portion and vacuum portion attached.

1 Claim, 10 Drawing Sheets
